UNITED STATES PATENT OFFICE

ARNOLD N. LURIE, OF CHICAGO, ILLINOIS

ARTICLE OF MANUFACTURE

Application filed May 22, 1931. Serial No. 539,646.

This invention relates to new and useful articles of manufacture and has particular reference to adjustable friction supports adapted for use in connection with drafting tables, kitchen cabinets, table leaf extensions, reclining chair backs, and other devices and appurtenances with which the invention may be combined or to which it may be applied. No attempt is made to show the many various uses to which the principles of this invention are adaptable, but the illustrations are confined to several modifications of the invention shown in connection with a draftsman's drawing table of table leaf extension.

The invention has among its objects to provide novel, adjustable, frictional supports which shall be simple in construction and susceptible to comparatively quick and positive operation.

With the above and other objects in view, my invention consists in the novel combination, construction and arrangement of the parts and members shown in the accompanying drawing, which shows various embodiments of my invention, the same being described in the following specifications, and particularly claimed in the appended claims.

Fig. 1 is a perspective view, partially in section, of my invention;

Fig. 2 is an elevation of same, the holding position being shown in dotted lines;

Fig. 3 is a modification showing a single pivotally mounted friction plate with a grip having a pair of jaws adapted to engage said plate and a third frictional holding means comprising a surface adapted to engage with in the guide;

Fig. 4 represents a perspective view of the grip;

Fig. 5 is a cross section taken on line 5—5 of Fig. 3.

Referring now to the illustrations disclosed in Figs. 1 and 2, the hinged extension 48 is supported on the member 49 which comprises a substantially laterally section 49^A formed at its inner end with a pair of downwardly disposed integral hinge ears 49^B for the pivotal pin 50. The outer end is provided with a pair of downwardly disposed extensions 49^C cast integrally with the lateral section 49^A

and having a shelf-like integral section 49^D at the bottom thereof. The extensions 49^C have a second lateral extension 49^E extending between them and extending parallelly and in spaced relation to the section 49^D.

A double forked friction bar 51 is hingedly supported on the pin 50 between the ears 52^A of the bracket 52 which is rigidly supported on the face 53 of the apparatus or device with which the hinged extension is used.

The double forked friction bar comprises a pair of spaced parallelly disposed forks 51^A, the free ends of which extend into the openings above the shelf 49^D and 49^E, thus limiting the up and down movement of same.

A substantially L-shaped gripping member 54 is provided which comprises a normally operable vertical arm 54^A disposed between the spaced forks 51^A and having enlarged upper and lower ends with laterally extending friction teeth 54^B and 54^C adapted to respectively engage upper and lower faces of each fork 51^A. The arm 54^A is further provided with integral lugs 54^D of rectangular cross section extending laterally from an intermediate portion of the arms 54 and on both sides thereof to provide a pair of additional friction teeth for engagement between the blades of the forks 51^A. The integral laterally extending arm 54^E is pivotally connected with a link 55 which is pivoted on the pin 56 within the ears cast integrally with the lower end of the bracket 52.

The upper end of the arm 54^E is of sufficient height to clear the under face of the section 49^A when the forks are in lateral position, so that when the extension 48 is raised to lateral position, as shown in the illustrations, the underside of 49^A will rest upon the head of the arm 54^A and will exert downward pressure thereon tending to lift the hinged end of the arm 54^E and will thereby cause a frictional engagement of the teeth 54^B, 54^C and 54^D with the forks 51^A.

In Fig. 2, the dotted lines indicate the retaining position of the link 55, grip 54, and forks 51^A; the full lines indicate the released position of same.

Referring now to the illustrations in Figs. 3, 4 and 5, the hinged member 57 is rigidly

mounted to the top of the member 58 of inverted U cross section having an integral cross shelf 58^A connecting the outer end of the vertical legs thereof.

5 A bracket 59 is rigidly supported below the movable member 57 and is provided with a pair of integral ears 59^A for the pin 60 about which is pivotally mounted the friction plate 61, the vertical movement of which is constrained between the lateral portion of the member 58 and the cross shelf 58^A.

10 A pair of links 62 is pivotally supported at their lower ends on the pin 63 held in the bracket 59. The upper ends of the links 62 are pivotally connected with the pin 64 held within the inner end of grip 65 which is pivotally supported on the pin 66. The outer end of the grip 65 is provided at its lower end with a tooth 65^A adapted to frictionally engage upon the upper face of the friction plate 61. A second frictional grip 67 of substantially inverted U cross section, is pivotally mounted on the pin 66 in a manner to present the upper lateral portion 67^A as a frictional bearing against the inner face of the lateral portion of the member 58; the vertical legs 67^B being disposed at the sides of the grip 65 for pivotal support on the pin 66.

15 A third grip 68 of substantially U shaped cross section is provided, the vertical legs 68^A of which are pivotally suspended from the ends of the pin 66. The lateral portion 68^B is formed with an integral tooth 68^C projected forwardly and located to fall substantially below the tooth 65^A and to frictionally engage the under side of the plate 61.

20 The member 57 in this instance will be automatically securely retained in lateral position by the friction between the underside of the lateral portion 58^B and the section 67^A and between the tooth 65^A and the upper face of plate 61, and between the lower face of plate 61 and the tooth 68^C. To release the frictional retainment of the member 57 it is only necessary to slightly raise the members 57, as for instance, to the position shown in dotted lines in Fig. 5, whereupon the relative gripping positions of the members 65^A, and 68^C will be displaced to permit a free sliding action of same on plate 61 to afford the lowering of the member 57 about the pivotal pin 60.

25 Having thus described my invention, what I claim as new and desire to secure by Letters Patent, is:

30 1. A device for frictionally retaining a hingedly mounted member in adjustably varying angular positions, comprising an element movable with an offset portion spaced from the face of said member, a frictional grip comprising an arm having an opening in one end thereof through which said offset portion of said element extends 35 for frictional engagement, a pivot pin in the

other end of said arm, a link connected with said pivot pin at one end thereof, and a stationary support for the other end of said link.

2. A device for frictionally retaining a hingedly mounted member in adjustably varying positions, comprising a hingedly mounted element movable with said member, and having a free limited movement independent of said member, said element comprising a pair of spaced forked sections, an arm adapted to frictionally engage said pair of forked sections along different points thereonto frictionally retain said member in adjustably varying angular positions, said arm having integral teeth for frictionally engaging the inner, upper and lower faces of said forked sections, a link connecting one end of said arm, and a stationary support for the other end of said link, said stationary support pivotally supporting said member and said element.

3. A device for frictionally retaining a hingedly mounted member in adjustably varying angular positions, comprising a hingedly mounted element movable relatively to said member, and having a free limited movement independent of said member, said element comprising a plate hingedly mounted at one end thereof, an inverted U-shaped member connected to said hingedly mounted member, said pivotally mounted member and said element and said inverted U-shaped member having an identical pivotal axis, a frictional grip comprising a friction shoe adapted to move between the lower face of said U-shaped member, a frictional grip arm pivotally mounted on said shoe above said plate element, and having means for frictionally engaging the upper face of said plate element, a link connecting one end of said grip arm, a stationary support for the other end of said link, and a U-shaped frictional grip also pivotally supported upon the same pivotal support of said arm and adapted to frictionally engage upon the lower face of said plate element.

4. A device as embodied in claim 3, and including said stationary support comprising a bracket having pivotal means for pivotally supporting said pivotally mounted member and said plate element and said inverted U-shaped member.

5. A device as embodied in claim 3, and including said friction shoe comprising a plate of inverted U-shaped cross section wherein the parallel downwardly disposed portions provide pivotal supports for said frictional grip arm and said U-shaped frictional grip.

6. In witness whereof I affix my signature.

ARNOLD N. LURIE.
